UNITED STATES PATENT OFFICE.

JIENRY S. KLEIN AND BENJAMIN F. KLEIN, OF MILWAUKEE, WISCONSIN.

STAMP-AFFIXER.

SPECIFICATION forming part of Letters Patent No. 637,393, dated November 21, 1899.

Application filed July 3, 1899. Serial No. 722,629. (No model.)

To all whom it may concern:

Be it known that we, HENRY S. KLEIN and BENJAMIN F. KLEIN, citizens of the United States, and residents of Milwaukee, in the county of Milwaukee and State of Wisconsin, have invented certain new and useful Improvements in Stamp-Affixers; and we do hereby declare that the following is a full, clear, and exact description thereof.

10 Our invention has for its object to provide a simple, economical, and convenient device for storing and affixing adhesive stamps. Therefore it consists in certain peculiarities of construction and combination of parts 15 hereinafter particularly set forth with reference to the accompanying drawings and subsequently claimed.

Figure 1 of the drawings represents a partly-sectional view of a device in accordance with 20 our invention, the view being indicated by lines 1 1 in the succeeding figure; Fig. 2, an elevation of the device, partly in section; Fig. 3, a plan view, partly in horizontal section on the plane indicated by line 3 3 in the preceding figure; Fig. 4, a plan view, partly in horizontal section on the plane indicated by line 4 4 in the second figure; Fig. 5, a perspective view of the stamp-magazine element 25 of said device inverted; Fig. 6, a similar view 30 of the stamp-pusher portion of the aforesaid device, and Fig. 7 a like view of the casing or stand portion of the same.

Referring by letter to the drawings, A indicates an elongated metal casing of rectangular contour in transverse section, the lower 35 end of the same being open and preferably flared at all sides to obtain greater supporting area and afford clearance for a sliding open-bottom metal shell B, constituting a 40 stamp-magazine, hereinafter more particularly described. Extending up from the top of the casing, central of the same, is a tubular guide C for a hollow shank D of an angular bail E, and a handle F is made fast on 45 the bail-shank.

A spiral spring G of suitable power, arranged under tension in the tubular guide C and shank D aforesaid, operates to automatically return the bail E to normal position 50 when pressure thereon is released.

The lower open end of the magazine B is shown provided with inwardly-extending

corner-flanges b, that serve as supports for a pile of stamps H, set in said magazine in opposition to a pusher I, consisting of an open-top metal shell provided with longitudinally-slotted arms J, that extend up through registering slots c d in the upper ends of the aforesaid magazine and casing, the working face of the shell-bottom being preferably faced with a strip e of felt or other suitable soft material. A light spiral spring K is arranged under tension between the upper end of magazine B and the pusher I to hold this pusher under pressure against the stamps supported in said magazine.

The casing A and stamp-magazine B are longitudinally slotted in register with the slots in arms J of the pusher I, and the registering slots are engaged by inwardly-extending ears f of the bail E, to which reference is had in the foregoing. The longitudinal slotting of the stamp-magazine with respect to the slots in the pusher-arms J is such that the two move together when the bail is forced down, initial pressure coming on said pusher-arms until by gradual diminishing of the pile of stamps, as hereinafter explained, the pressure comes directly upon said magazine.

In practice the stamps are piled in the magazine B to have their adhesive faces downward and that portion of an envelop or other surface to be stamped is moistened preliminary to an operation of our device, the latter being then set over the moistened surface and its bail pushed down. This operation brings the adhesive side of the lowermost stamp in forcible contact with the moistened surface, where it adheres and pulls away from the supporting corner-flanges of the magazine, 90 when pressure upon said bail is released to permit retraction of said magazine incidental to expansion of the spring in the bail-shank and the tubular guide for same.

In conjunction with a stamp-affixing device of the genus above specified we may provide a moistener, and we herewith illustrate such an organization. The moistener herein shown consists of a water-holder L, having a lower end spout plugged with a protruding fold M of felt or other suitable absorbent material, said receptacle being provided with a filling-aperture and detachably connected to a side of the casing of the stamp-affixing de-

vice. The back of the water-holder herein shown is countersunk about its filling-aperture *g*, and a compressible gasket *h* is laid in the countersink to be compressed against the 5 casing of the stamp-affixing device, and thereby exclude air from said water-holder. This exclusion of air prevents flow of the water in the holder, the material protruding from the lower end spout of said holder being kept 10 moist by absorption. At its lower end the back of the illustrated water-holder is provided with an elongated horizontal eye *j* for the engagement of a corresponding hook *k*, projecting from the adjacent side of the 15 stamp-affixer casing, and a spring-latch *m*, fast on the top of said water-holder, engages with the top of said casing; but we do not limit ourselves to a detachable moistener nor to one that is necessarily in rigid connection 20 with the stamp-affixer.

To utilize the combined moistener and stamp-affixer herein particularly shown and described, the machine as a whole is tilted in the hand to permit of the protruding absorbent material of said moistener being swept 25 along the surface to be moistened, after which said machine is brought to an upright position and the bail portion thereof operated in the manner above described to discharge the 30 requisite number of stamps one by one upon the moistened surface.

While we have shown and described a preferred construction and arrangement of parts constituting a combined surface-moistener 35 and stamp-affixer, the details of the machine may be considerably varied without departure from the scope of our invention.

Having thus described our invention, what we claim as new, and desire to secure by Letters Patent, is—

1. An adhesive-stamp affixer comprising an upright casing open at its lower end and provided with an upwardly-extending tubular guide, a bail having a tubular shank loose on 45 the guide, a spiral spring under tension in said guide and bail-shank, a stamp-magazine

loose in the casing and having its lower end open but provided with inwardly-extending supports, and a stamp-pusher loose in the magazine, this stamp-pusher and said magazine being in conjunction with the bail to reciprocate with the same. 50

2. An adhesive-stamp affixer comprising an upright casing open at its lower end and provided with longitudinal side slots as well as 55 an upwardly-extending tubular guide and top slots, a stamp-magazine loose in the casing and also provided with longitudinal side slots and top slots, a stamp-pusher loose in the magazine and provided with longitudinally-slotted arms engaging the top slots in 60 said magazine and casing, a spiral spring under tension against the stamp-pusher, a bail having a tubular shank loose on the aforesaid guide, a spiral spring under tension in said 65 guide and bail-shank, and bail-ears engaging the slots longitudinally of the aforesaid casing, stamp-magazine and pusher-arms.

3. An adhesive-stamp affixer comprising an upright casing open at its lower end, a stamp-magazine loose in the casing and provided at 70 its open lower end with inwardly-extending supports, a stamp-pusher loose in the magazine, and a spring-controlled bail operative in conjunction with the stamp-pusher and magazine to reciprocate the same; together with a water-receptacle, in detachable connection with said casing, provided with a countersunk filling-aperture surrounded by a compressible gasket facing the aforesaid casing, 75 and a plug of absorbent material protruding from a lower end spout of said receptacle. 80

In testimony that we claim the foregoing we have hereunto set our hands, at Milwaukee, in the county of Milwaukee and State of Wisconsin, in the presence of two witnesses. 85
